(57) **CLAIM**

The ornamental design for an insulated container, as shown and described.

DESCRIPTION

FIG. 1 is a perspective view of an insulated container, showing a preferred embodiment of my new design, as taken from the front, left.

FIG. 2 is a front elevation of the insulated container of FIG. 1, the rear elevation being substantially a mirror image thereof.

FIG. 3 is a right end elevation of the insulated container of FIG. 1, the left end elevation being substantially a mirror image thereof.

FIG. 4 is a bottom plan view of the insulated container of FIG. 1; and,

FIG. 5 is a top plan view of insulated container of FIG. 1. A handle is shown in broken lines in FIG. 1 for illustrative purposes only and forms no part of the claimed design. Portions of the insulated container are shown broken away in FIGS. 1, 2 and 3 to indicate indeterminate height.
